US00D776295S

(12) **United States Design Patent** (10) **Patent No.:** **US D776,295 S**
Wainwright et al. (45) **Date of Patent:** **** Jan. 10, 2017**

(54) **BASE**

- (71) Applicant: **Charles River Laboratories, Inc.**,
Wilmington, MA (US)
- (72) Inventors: **Norman R. Wainwright**, Johns Island,
SC (US); **Dana M. Nutter**, Charleston,
SC (US); **Eric Stimpson**, Charleston,
SC (US); **Al Fuchs**, Charleston, SC
(US); **Thomas Preidel**, Uslar (DE)
- (73) Assignee: **Charles River Laboratories, Inc.**,
Wilmington, MA (US)
- (**) Term: **14 Years**
- (21) Appl. No.: **29/508,248**
- (22) Filed: **Nov. 4, 2014**
- (51) LOC (10) Cl. **24-02**
- (52) U.S. Cl. **D24/224**

CLAIM

The ornamental design for a base, as shown and described.

DESCRIPTION

FIG. 1 is a top perspective view of a base;

FIG. 2 is a front view of the base;

FIG. 3 is a right side view of the base;

FIG. 4 is a left side view of the base;

FIG. 5 is a top view of the base;

FIG. 6 is a bottom view of the base;

FIG. 7 is a cross-sectional view of the base taken along line 7-7 seen in FIG. 5; and,

FIG. 8 is a bottom perspective view of the base.
